UNITED STATES PATENT OFFICE.

GEORGE SCHWARZ AND JOSEF AMON, OF NEW YORK, N. Y.

STARTING DEVICE FOR MERCURY-VAPOR APPARATUS.

No. 893,816.

Specification of Letters Patent.

Patented July 21, 1908.

Application filed March 26, 1906. Serial No. 307,980.

To all whom it may concern:

Be it known that we, GEORGE SCHWARZ, a subject of the Emperor of Germany, residing in the city of New York, in the county and State of New York, and JOSEF AMON, a subject of the Emperor of Austria-Hungary, residing in the city of New York, county and State of New York, have jointly invented certain new and useful Improvements in Starting Devices for Mercury-Vapor Apparatus, of which the following is a specification.

This invention relates to apparatus in which an inclosed gas or vapor is included in an electric circuit.

15 The object of the invention is first, to provide improved automatic means for initiating or starting the circuit in which the gas or vapor is included; second, to furnish a compact commercial form of lighting device or 20 lamp in which a gas or vapor is included in the circuit; third, to provide a lamp of the character described which can be applied to the ordinary form of incandescent lamp sockets, such as is in common commercial 25 use; and fourth, to improve and simplify the construction of the mercury vapor lamp.

The accompanying drawings illustrate the invention:

Figure 1 represents a vertical section of a 30 lamp; Fig. 2 is a section of the starting device on line *a*—*a*, Fig. 1; Fig. 3 is a vertical section of the socket containing the electro-magnet and auxiliary devices; Fig. 4 is a 35 sectional view on the line *b*—*b*, Fig. 3; Figs. 5, 6, 7 and 8 are modified forms of the initial arc starting device.

In Fig. 1, *e* is the glass inclosing bulb of the lamp; it may be cylindrical or of any suitable form. At the bottom of the bulb *e*, 40 and integral therewith, is an auxiliary cell *d*; the cell *d* is connected with the interior of the bulb *e* by a passage *f*. The bulb *e* is enlarged at the top where there is a solid section of glass *g*, for the purpose of receiving 45 the connecting devices to be described. There is a rod of glass *h* extending from one end of the bulb to the other at about the axial line. The rod *h* is bifurcated at the bottom, the two legs being shown at *i* and *j*. 50 In rod *h* is a contracted passage 12 extending from one end to the other, passing through the leg *j* to a point on the exterior of the bulb *e*; a similar passage 13 extends from end to end of the rod *h* through the leg *i* terminating on the interior of the bulb *e* 55 near the bottom thereof. There are two

rings or enlargements 14, 15, on the rod *h* near the top thereof between which the metal anode *m* is fixed, the cathode, consisting of a body of mercury *n*, is placed in the bottom of the bulb *e*. In the passage *f* connecting the cell *d* with the bulb *e*, there is a metallic wire *w*, preferably of platinum, incased in a cylinder of vitreous enamel *v*; the exterior diameter of *v* is approximately 60 the same as the interior of the passage *f*, due allowance being made for a reasonable degree of expansion. The wire *w* with its coating of enamel *v* forms a plunger or piston like device *x*, which slides in the passage *f*. 70 The wire *w* with its insulating coating is curved at the top, as shown at *z*, so that one free end of the wire 16 contacts with the mercury *y* while the other free end 17 contacts with the mercury *n* in the bulb *e*. 75 The cell *d* is filled with a thermal device or material *y* which has a high co-efficient of expansion and contraction on being subjected to variations of temperature. Mercury is preferred because its expansive 80 property under the effect of increasing heat is sufficiently marked. Normally the wire *w* electrically unites the mercury *n* and the mercury *y*. In close proximity to the mercury *y* there is a heat coil *q*; this consists of 85 a number of convolutions of insulated wire having suitable resistance. It is preferred to provide a helical groove 20 on the exterior of the cell *d* to receive this heat coil *q*; and to protect it by a shell or cover of insulating 90 material 21. One end of the heat coil *q* passes through the wall of the cell *d* to make electrical contact with the mercury *y*, the other end of the coil is connected to the insulated conductor 112 which in turn is connected to the contact 22. The conductor 113 connects the mercury *n* with the contact 23; contact 24 is electrically connected with the anode *m* by conductor 40; the contacts 22, 23, and 24 on the base of the lamp register with corresponding contacts in a fixed socket, all arranged substantially like those in the well known Edison incandescent lamp. The circuit connections exterior to the lamp are diagrammatically represented 100 in Fig. 1, and a mechanical arrangement of a suitable socket is shown in Fig. 3.

Referring to Fig. 3 a porcelain section *p* forms the basis of the socket; within the shell *p* is an electro-magnet 30 having a hollow core 31, an armature 32 elevated by a compression spring 33, and a collar 34 of

non-magnetic material fixed to the armature 32 to guide its movements with respect to the core. 35 is a contact stop for the armature 32; armature 32 is electrically connected with the contact 122, through the spring 33, the core 31 and electrical conductor 36. The ring 124 is electrically connected with one terminal of magnet 30 by the screw 46 and the screw threaded shell 123 is electrically connected to the binding post 37 by the screw 38. The binding post 39 is electrically connected to one terminal of the resistance coil *r* and to the second terminal of electro-magnet coil 30. These circuits are shown diagrammatically in Fig. 1, where *s* is a hand operated double pole switch.

The operation of the apparatus is as follows: When the switch *s* is closed the mains are connected with the lamp circuit. Current passes to post 39, resistance *r*, contact 35, armature 32, contact 122, contact 22, conductor 112, heat coils *q*, mercury *y*, wire *w*, mercury *n*, wire 113 to contact 23 to 123 to switch *s*. Mercury *y* under the effects of the current in heat coil *q* expands, immediately lifting the plunger *x* and breaking contact between the wire terminal 17 and the surface of the mercury *n*, where an arc forms, vapor is generated and an arc is sprung between the anode *m* and the cathode *n* enveloping the tube *h*, which thereby casts no shadow. When the circuit is broken at 17 a new circuit is established through 39 via 30, 124, 24, 40, anode *m*, the vapor arc, mercury *n*, conductor 113 to 23, to 123 to switch *s*; armature 32 is attracted and the circuit through resistance *r*, conductor 112, including wire *w*, is opened between 32 and 35. The inclosing bulb *e* is strengthened by the rod *h* and the luminous gas or arc envelops rod *h* thus avoiding a shadow. The conductors 112 and 113 are located in tube *h* by preference but in Figs. 6, 7 and 8, these conductors are placed in the wall of the bulb *e*. In Fig. 5, the heat coil *q* is placed inside the cell *d*; there is a glass stem 60 covered with asbestos 61 and this is surrounded by an iron sleeve 62. The heat coil *q* is located on this iron core and is insulated with a vitreous enamel coating 63. One end of the heat coil *q* connects with the mercury, the other end is connected with the wire 112, and the contact 22. The operation is the same as that described in respect to Fig. 1.

In Fig. 6 the plunger *x* carries a cup 50 having a slotted perforation at 51. When the plunger is forced upward into the position shown in dotted lines the mercury flows through the perforation and when the flow stops an arc is formed.

In Fig. 7 the heat coil is shown at the top of the bulb *e*; when the plunger *x* is forced upward an arc is formed between the terminal of the wire at 17 and the anode *m*.

In Fig. 8 the starter is located in the top

of the bulb *e*, the other parts being as shown in Fig. 1. One end 16 of the plunger *x* extends into the mercury *y* in the cell *d*. The end 17 of the plunger wire extends down into the mercury *n* in the bottom of the bulb *e*, located as shown in Fig. 1. The operation of these modified devices is substantially the same as above described.

In Figs. 7 and 8 where the auxiliary cell *d* is located at the top of bulb *e* there is a transverse brace or partition *t* preferably of glass arranged to support the cell *d*.

What we claim and desire to secure by Letters Patent is:

1. The combination in an apparatus of 80 the character described of two electrodes, a circuit therefor, and a branch circuit including a plunger and a heat coil to control the plunger.

2. The combination in apparatus of 85 the character described of two electrodes, a circuit therefor, and a starting device in a branch circuit consisting of a movable contact and a thermal controller therefor.

3. The combination in an apparatus of 90 the character described of two electrodes, a circuit therefor, and a starting device consisting of a movable, arcing contact and a controlling device therefor operated by heat.

4. The combination in an apparatus of 95 the character described of two electrodes, a circuit therefor, a starting device in a branch circuit consisting of a movable contact, a thermal controlling device and means for opening the branch circuit and establishing 100 the main circuit.

5. The combination in a vapor lamp of two main electrodes, an inclosing bulb therefor, an auxiliary cell forming part of said bulb, a passage between the cell and bulb, 105 a thermal device in close proximity to the cell, a plunger in the passage normally connecting the thermal device with the cathode, main circuit connections for the main electrodes, a branch circuit including said plunger and means for opening the branch circuit and closing the main circuit.

6. The combination in a vapor lamp of 110 two main electrodes, an inclosing bulb therefor, an auxiliary cell forming part of said bulb, a passage between the cell and bulb, a thermal device in close proximity to the cell, a plunger in the passage normally connecting the thermal device with the cathode, main circuit connections for the main electrodes; a branch circuit including said plunger, means for automatically opening said branch circuit and means for closing the main circuit.

7. The combination in a vapor lamp of 115 two main electrodes, an inclosing bulb therefor, an auxiliary cell forming part of said bulb, a passage between the cell and bulb, a body of mercury in the cell, a plunger in the 120 passage electrically connecting the main, 130

mercury electrode with the mercury in the cell, main circuit connections for the main electrodes, a branch circuit including said plunger, means for opening the branch circuit and means for closing the main circuit.

8. The combination in a vapor lamp of two main electrodes, an inclosing bulb therefor, an auxiliary cell forming part of said bulb, a passage between the cell and bulb, a body of mercury in the cell, a plunger in the passage electrically connecting the mercury electrode with the mercury in the cell, a heat coil for the auxiliary cell, main circuit connections for the main electrodes, a branch circuit including said plunger and coil means for automatically opening the branch circuit and means for closing the main circuit.

9. In an apparatus of the character described the combination with the main electrodes of a separable contact, main circuit connections for the main electrodes, a branch circuit for the separable contacts, means for automatically opening the branch circuit means for automatically closing the main

circuit and passages in the walls of the inclosing device for the conductors of said circuits.

10. The combination in a vapor lamp of an inclosing bulb, electrodes in the bulb, an arc starting device carried on said bulb, a base for said lamp, fixed contacts on said base, electrical connections between the electrodes and arc starting device and said contacts, a suitable fixed socket, fixed contacts in the socket forming the terminals of main line and branch circuit connections, an electromagnetic switch in said socket suitably connected to said contacts and means for mechanically and separably uniting the lamp base with said socket whereby electrical contacts on the base register with corresponding electrical contacts in the socket.

GEORGE SCHWARZ.
